UNITED STATES PATENT OFFICE.

RICHARD EDWIN RAXWORTHY, OF EAST DULWICH, ENGLAND.

COLLAPSIBLE GATE.

1,009,099.

Specification of Letters Patent. Patented Nov. 21, 1911.

Application filed February 23, 1910. Serial No. 545,379.

To all whom it may concern:

Be it known that I, RICHARD EDWIN RAXWORTHY, a subject of the King of England, residing at 17 Matham Grove, East Dulwich, in England, have invented certain new and useful Improvements in Collapsible Gates, of which the following is a specification.

This invention relates to improvements in collapsible gates of the type generally known as lattice gates. These gates consist broadly of two sets of lattice bars, one set of bars crossing the other set and the vertical pickets having pivots connecting the pickets with the lattice bars at the point of crossing of the bars.

According to this invention in addition to the customary pickets, intermediate picket-like members are employed but the arrangement is such that when the gate is contracted, that is to say, when all the pickets are close together, the intermediate picket-like members will not take up any extra room, but will allow the gate to fold up in the same width as it would do if the intermediate members were not present.

This invention will now be described with reference to the accompanying drawings, in which:—

Figure 1 shows one construction of gate in its extended position and partly broken away. Fig. 2 illustrates the gate in its contracted position, Fig. 3 is a view of a modified construction of gate extended and partly broken away. Fig. 4 shows a modification in the intermediate picket-like members. Fig. 5 is a sectional detail on the line 1—1 of Fig. 1, Fig. 6 is a sectional detail on the line 2—2 of Fig. 1, Fig. 7 is a sectional detail on the line 3—3 of Fig. 1, Fig. 8 is a sectional detail on the line 4—4 of Fig. 1, Fig. 9 is a sectional detail on the line 5—5 of Fig. 1, Fig. 10 is a sectional view of a modified construction of picket and its connection to the lattice bars and Fig. 11 is a further modification of picket. Figs. 5—11 are drawn to a larger scale than Figs. 1—4.

Two sets of pickets A and A¹ are arranged in the customary manner to slide in guides B, B¹, one set of pickets A being on one side of the guide bar, and the other set of pickets A¹ being on the other side thereof, the members of the two sets registering with each other. On the inner side of the pickets A and pivotally secured thereto as at D, is a set of lattice bars C as shown

more particularly in Figs. 7, 8 and 9. The pivots are not each denoted by reference letters in Figs. 1, 2, 3 and 4, but are denoted by way of example. Pivoted as at D¹ to the other side of the pickets A¹ is a second set of lattice bars C¹. The pivots D however, only connect the pickets A and the lattice bars C, while the pivots D¹ only connect the pickets A¹ and the lattice bars C¹. The lattice bars C are arranged so that they cross the lattice bars C¹ in the well-known and customary manner in gates of this construction. Intermediate members E are pivoted to the lattice bars C, C¹ at the points of crossing of the bars as illustrated at F¹ in Figs. 5 and 6. The intermediate members E are parallel to the pickets A or A¹. They do not however, extend to the guides B or B¹.

In the construction illustrated in Fig. 1, the gate is comprised of two complete and separate lattice constructions, one of which is pivoted by the stationary pivots G, and the other by the stationary pivots G¹ to the pickets. The pivots G and G¹ do not pass through both the sets of lattice bars but are arranged in the manner described with reference to Figs. 7, 8 or 9. The pickets are slotted as at H or H¹ to allow the meeting ends of the lattice bars to move in the vertical direction. The intermediate bars E also have slots F formed in them for the same purpose. The pivots referred to in Fig. 1 as G and G¹ are equivalent to the pivots D of Fig. 7.

Figs. 10 and 11 show in section the modified forms of pickets with lattice bars pivoted thereto. In Fig. 10 pickets A and A¹ are shown as slotted bars and the bolts D and D¹ have enlarged heads which work in the slots. In Fig. 11 the pickets A and A¹ are shown as channel bars and the pivots in this case also have enlarged heads which work in the channels. The elevation of a gate constructed in either of these forms is shown in Fig. 3.

In Fig. 4 the pickets are shown as having bolts J connecting each picket of one set with the picket of the other set which registers with it. The bolts J are situated in the pickets midway between two sets of lattice structures. The intermediate bars E are deformed at a position opposed to the bolts J, and in the particular construction illustrated, the intermediate members are given a twist.

When the gate, as illustrated in either Figs. 1, 3 or 4 is contracted as shown in Fig. 2, the intermediate members slide in between the pivots D or D¹ as illustrated in Figs. 7, 8 or 9. Thus, although extra picket-like members have been provided, the gate contracts into the same width as it would do, had the intermediate members not been present. Thus, the advantage of having extra bars or members in the formation of a gate is also combined with the advantage of allowing the gate to contract into the width not larger than heretofore. It is obvious that, with the construction described with reference to Fig. 4 as the intermediate members are deformed at the points opposed to the transverse bolts J, it will still be possible for the intermediate members to pass in between the pivots D and D¹.

What I claim as my invention and desire to secure by Letters Patent is:—

1. In a collapsible lattice gate, the combination with two sets of lattice bars, one set of bars crossing the other set, of two sets of pickets, one set pivoted to the outer sides of one set of lattice bars and the other set pivoted to the outer sides of the second set of lattice bars, thereby leaving an unobstructed space between adjacent picket bars, of the two sets, and a set of intermediate picket-like members pivoted between the two sets of lattice bars at the point of crossing of said lattice bars, whereby when the gate is collapsed the intermediate picket members may slide between the main pickets and lattice bars.

2. In a collapsible lattice gate the combination of two sets of lattice bars, one set of bars crossing the other set, a set of pickets pivoted to the outer sides of one set of bars, another set of pickets pivoted independently of the first set of pickets to the outer sides of the second set of bars, the members of one set of pickets registering with those of the other set and a set of intermediate picket-like members pivoted between the two sets of lattice bars at the point of crossing of one set over the other.

3. In a collapsible lattice gate the combination of two sets of pickets, the members of one set registering with those of the other set, transverse bolts connecting pairs of opposing picket members, a set of lattice bars pivoted to the inner sides of one set of pickets, another set of lattice bars crossing those of the first set and pivoted to the inner sides of the second set of pickets, the bars being interrupted in the region of the transverse bolts, and a set of intermediate picket-like members pivoted between the two sets of lattice bars at the point of crossing of one set over the other and each deformed at a point opposed to the transverse bolts, the lattice bars being slidably pivoted to the pickets and intermediate bars.

interrupted in the region of the transverse bolts, and a set of intermediate picket-like members pivoted between the two sets of lattice bars at the point of crossing of one set over the other, and each deformed at a point opposed to the transverse bolts.

4. In a collapsible lattice gate, the combination of two sets of lattice bars, one set of bars crossing the other set, a set of pickets pivoted to the outer sides of one set of bars, another set of pickets pivoted independently of the first set of pickets to the outer sides of the second set of bars and a set of picket-like members pivoted between the two sets of lattice bars at the point of crossing of one set over the other, the lattice bars being slidably pivoted to the pickets and intermediate bars.

5. In a collapsible lattice gate, the combination of two sets of lattice bars, one set of bars crossing the other set, a set of pickets pivoted to the outer sides of one set of bars, another set of pickets pivoted independently of the first set of pickets to the outer sides of the second set of bars, the members of one set of pickets registering with those of the other set and a set of intermediate picket-like members pivoted between the two sets of lattice bars at the point of crossing of one set over the other, the lattice bars being slidably pivoted to the pickets and intermediate bars.

6. In a collapsible lattice gate, the combination of two sets of pickets, the members of one set registering with those of the other set, transverse bolts connecting pairs of opposing picket members, a set of lattice bars pivoted to the inner sides of one set of pickets, another set of lattice bars crossing those of the first set and pivoted to the inner sides of the second set of pickets, the bars being interrupted in the region of the transverse bolts, and a set of intermediate picket-like members pivoted between the two sets of lattice bars at the point of crossing of one set over the other and each deformed at a point opposed to the transverse bolts, the lattice bars being slidably pivoted to the pickets and intermediate bars.

In testimony whereof I have signed my name to this specification in the presence of two subscribing witnesses.

RICHARD EDWIN RAXWORTHY.
